DESIGN FOR AN ELECTRIC STOVE

Carl J. Weinhardt and George A. Danneker,
Indianapolis, Ind., assignors to Liberty Electric
Company, Indianapolis, Ind., a corporation of
Indiana

Application June 9, 1933, Serial No. 48,362

Term of patent 7 years

To all whom it may concern:

Be it known that we, CARL J. WEINHARDT and
GEORGE A. DANNEKER, citizens of the United
States, residing at Indianapolis, in the county of
Marion and State of Indiana, have invented a
new, original, and ornamental Design for Elec-
tric Stoves, of which the following is a specifi-
cation, reference being had to the accompan-
ying drawing, in which

The figure is a perspective view of an electric
stove, showing our new design.

The dominant features of the design reside in
the ornamental supports.

We claim:

The ornamental design for an electric stove,
as shown and described.

In witness whereof, we have hereunto set our
hands at Indianapolis, Indiana, this 7th day of
June, A. D. one thousand nine hundred and thir-
ty-three.

CARL J. WEINHARDT.
